(57) **CLAIM**

The ornamental design for an inward curved partition panel as shown and described.

DESCRIPTION

FIG. 1 is an upper perspective view of the inward curved partition panel showing my design.

FIG. 2 is a front elevation view thereof;

FIG. 3 is an enlarged perspective view thereof, taken from portion "3" in FIG. 2;

FIG. 4 is a back elevation view thereof;

FIG. 5 is a side elevation view thereof;

FIG. 6 is an opposite side elevation view thereof;

FIG. 7 is an enlarged perspective view thereof, taken from portion "7" in FIG. 6;

FIG. 8 is a top plan view thereof;

FIG. 9 is a bottom plan view thereof; and,

FIG. 10 is an upper perspective view thereof, showing the inward curved partition panel in a state of use.

The dash-dash broken lines in the drawings represent portions of the inward curved partition panel and form no part of the claimed design. The other broken lines in FIG. 10 represent environmental subject matter only and form no part of the claimed design. The dash-dot-dash broken lines shown in FIGS. 1 through 10 indicate that any portion of the inward curved partition panel beyond what is shown forms no part of the claimed design.

The dash-dot-dot broken lines of FIGS. 2, 3, 6, and 7 are included to show a partially enlarged view only and form no part of the claimed design.
